[57] CLAIM

We claim the ornamental design for a postmix beverage dispenser, as shown and described.

DESCRIPTION

FIG. 1 is a top front left side perspective view of a postmix dispenser showing our new design;

FIG. 2 is a front elevational view thereof;

FIG. 3 is a rear elevational view thereof;

FIG. 4 is a right elevational view thereof;

FIG. 5 is a left elevational view thereof;

FIG. 6 is a top plan view thereof; and,

FIG. 7 is a bottom plan view thereof.
